CLAIM

The ornamental design for a brain stimulation device, as shown and described.

DESCRIPTION

FIG. 1 is a perspective view of a brain stimulation device.

FIG. 2 is a front view of the brain stimulation device.

FIG. 3 is a top view of the brain stimulation device.

FIG. 4 a view of the left side of the brain stimulation device.

FIG. 5 is a view of the right side of the brain stimulation device.

FIG. 6 is a rear view of the brain stimulation device.

FIG. 7 is a bottom view of the brain stimulation device.

FIG. 8 is another perspective view of the brain stimulation device; and,

FIG. 9 is yet another perspective view of the brain stimulation device.

The broken lines depict portions of the brain stimulation device that form no part of the claimed design.

1 Claim, 9 Drawing Sheets
